UNITED STATES PATENT OFFICE.

GEORGE BOHNER, OF CHICAGO, ILLINOIS.

DESIGN FOR A CONNECTING-BRACKET FOR LAMP-FIXTURES.

SPECIFICATION forming part of Design No. 32,123, dated January 23, 1900.

Application filed November 16, 1899. Serial No. 737,260. Term of patent 3½ years.

To all whom it may concern:

Be it known that I, GEORGE BOHNER, a citizen of the United States, residing at Chicago, in the county of Cook and State of Illinois, have invented and produced a new and original Design for Connecting-Brackets for Lamp-Fixtures; and I do hereby declare the following to be a full, clear, and exact description of the same, reference being had to the accompanying drawings, forming a part of this specification, and in which—

Figure 1 is a front elevation, and Fig. 2 a side elevation, of a connecting-bracket for lamp-fixtures embodying the present invention.

This invention relates to a new and original design for a connecting-bracket for hydro-carbon incandescent lamp-fixtures, and the leading feature thereof consists in the design as herein shown and described.

As shown in the drawings, the connecting-

bracket is formed with a cylindrical main or body portion 1, a transversely-rounded lower end 2, in which is formed a transverse hole or orifice 3, and intermediate of its vertical height with the horizontal cylindrical necks 4 and 5, arranged at right angles to each other in a horizontal plane. The one has a plain exterior, while the other is externally screw-threaded, as shown.

Having thus fully described my said invention, what I claim as new, and desire to secure by Letters Patent, is—

The design for a connecting-bracket for lamp-fixtures, as herein shown and described.

In testimony whereof witness my hand this 4th day of November, 1899.

GEORGE BOHNER.

In presence of—

ROBERT BURNS,
H. A. NOTT.
